UNITED STATES PATENT OFFICE.

DAVID WILSON GREIG, OF MILLIKEN, NEW YORK.

DESIGN FOR A BOTTLE OR FLASK.

No. 39,231.

Specification for Design.

Patented March 31, 1908.

Application filed November 9, 1907. Serial No. 401,527. Term of patent 14 years.

To all whom it may concern:

Be it known that I, DAVID W. GREIG, of Milliken, Richmond county, and State of New York, and residing thereat, and a citizen of the United States, have invented a new, original, and ornamental Design for Bottles and Flasks, of which the following is a specification, reference being had to the accompanying drawing, forming part thereof, and in which—

The figure is a perspective view of a bottle or flask showing my new design.

I claim:

The ornamental design for a bottle or flask, as shown.

DAVID WILSON GREIG.
